UNITED STATES PATENT OFFICE.

OLIVER LEE, OF NEW YORK, N. Y., ASSIGNOR TO EBERHARD FABER PENCIL COMPANY,
OF BROOKLYN, NEW YORK, A CORPORATION OF NEW YORK.

DESIGN FOR A DISPLAY-RACK.

41,539.

Specification for Design.

Patented July 4, 1911.

Application filed March 12, 1910. Serial No. 549,067. Term of patent 7 years.

To all whom it may concern:

Be it known that I, OLIVER LEE, a citizen of the United States, residing in the city, county, and State of New York, have invented a new, original, and ornamental Design for Display-Racks, of which the following is a specification, reference being had to the accompanying drawing, forming part thereof.

The figure is a perspective view of a display rack showing my new design.

I claim:

The ornamental design for a display rack, as shown.

OLIVER LEE.
